UNITED STATES PATENT OFFICE.

RAY H. MANSON, OF ELYRIA, OHIO, ASSIGNOR TO THE GARFORD MANUFACTURING COMPANY, OF ELYRIA, OHIO, A CORPORATION OF OHIO.

CIRCUIT-CONTROLLER.

1,203,641.

Specification of Letters Patent. Patented Nov. 7, 1916.

Application filed September 29, 1913. Serial No. 792,256.

To all whom it may concern:

Be it known that I, RAY H. MANSON, a citizen of the United States, residing at Elyria, in the county of Lorain and State of Ohio, have invented certain new and useful Improvements in Circuit-Controllers; and I do hereby declare the following to be a full, clear, and exact description of the invention, such as will enable others skilled in the art 10 to which it appertains to make and use the same.

My invention relates to circuit controllers, and especially to circuit controllers adapted for use upon motor cycles for such purposes 15 as controlling an electric horn used for a warning signal device upon the motor cycle.

As is well known the motor cycle frame and handle bars are already well loaded with apparatus employed in the controlling and 20 operation of the vehicle and no controller would be considered which was not compact and convenient, as well as attractive in appearance. Owing to the speeds at which these machines are operated and to the rapidity with which they approach the persons to be warned, it is necessary that the 25 circuit controller should be convenient and should be of such construction as not to catch upon the clothing of the rider or otherwise interfere with his operation of the machine and at the same time be readily accessible. It is also necessary to provide a durable and substantial piece of apparatus for 30 this use, since being located upon the handle bars for convenience, it is frequently struck or engages objects upon which the motor cycle is rested.

Another object of my invention is to produce an attractive and ornamental circuit 40 controller.

Another object of my invention is to produce a circuit controller for furnishing two tones to the horn.

Other objects of my invention and the invention itself will probably be better understood from a description of the particular embodiments of the invention illustrated in the drawings.

Figure 1 is a side elevation of one embodiment of my invention. Fig. 2 is a side elevation showing the circuit controller in section. Fig. 3 is a section through the center line of a second embodiment of my invention. Fig. 4 is a perspective view of the modification 55 shown in Fig. 3. Fig. 5 is a section through

the center line of a third embodiment of my invention.

Referring now to the drawings and to the embodiments of my invention illustrated therein, at 6 is shown the casing of a circuit controller; at 7, suitable means for fastening the parts together, here shown as a screw; at 8, a push button for operating the circuit controller and at 9 and 10, suitable means for connecting it to the handle bars 65 of the motor cycle.

In the embodiment shown in Fig. 1 the push button 8 is formed with a finger catch, preferably by depressing the end of the contact-spring 11, as shown at 12. The casing 70 consists of a bottom member 13, preferably open at one end 14 and partially closed at the other end 15, the end 15 being provided with an opening 16 through which the conductors are led into the casing. The top 17 75 of the casing may be depressed, as shown at 18, to form a seat for the head 19 of the screw 7, thus sinking the head below the surface of the top and making it impossible for it to catch the clothing of the operator. At 80 20 is shown a second contact-spring carrying a contact 21, which may be formed by striking up a portion of the spring 20. This spring is provided with a terminal 21' adjacent the opening 16. The springs 11 and 85 20 are separated by insulating material 22 and the spring 20 is separated from the bottom of the casing by an insulating member 23. The springs and insulating members are fastened together and to the casing, preferably to the bottom, by the screws 7 and 24. 90

In the form shown in Figs. 3 and 4, the casing is shown at 30, the casing bottom at 31 struck up at 32 to fit over the handle bars of the motor cycle. The end 33 of this casing may be formed by bending up the end of the bottom. The end 33 is provided with an opening 34 through which the conductors may be led into the casing. The contact-springs are shown at 35 and 36. The contact spring 35 carries a contact 37 and the spring 36, a contact 38. These springs are separated from each other by suitable insulating material 39 and the springs and insulating material are connected to the casing 105 by any suitable means, preferably to the bottom of the casing by screws 40 and 41. The terminals 42 and 43 of the springs 35 and 36 are shown connected to the electric conductors. I provide operating means for the 110

springs, here shown as a spring member 44 supported from the casing, preferably by connecting one end 45 of the member 44 to the top of the casing by any suitable means, such as rivets 46.

The free end 47 of the member 44 is extended outside of the casing, preferably through the open end 48 of the casing. This free end may be bent over as shown at 48' 18 and extended down adjacent the top of the handle bars, where it is turned outwardly as shown at 49, forming a catch for the operator's finger. In the form shown in Figs. 3 and 4 this is folded over as shown at 50 15 in an arc-shaped segment whose sides are substantially parallel to the top of the handle bars. By this construction I make it possible to keep the catch so close to the handle bars that it will not catch inadvertently the clothing of the operator or apparatus employed adjacent to the handle bars.

A resistance device 51 constitutes a part of this circuit controller and is shown in 25 the shape of a coil mounted upon the spring 36. This circuit controller is provided with a contact 52 which engages a portion 53 of the spring 35 when the member 44 is depressed, the spring 35 being moved by the 30 member 44 through a stud 54, here shown of insulating material. The contacts 52 and 53 engage before the contacts 37 and 38, closing the circuit of the horn or other electro-responsive device connected in the circuit with 35 my circuit controller. The current through this circuit courses through the resistance device 51. To eliminate this resistance device and increase the flow of current through the circuit and thereby the sound of the 40 horn, more pressure is applied to the catch 50, so that the contacts 37 and 38 now engage, shunting the resistance device 51. Suitable means, such as a strap 57 may be employed to connect the circuit controller 45 shown in Figs. 3 and 4 to the handle bars of the motor cycle.

In the form shown in Fig. 5, the end 60 is closed, an opening 61 being provided for the member 62 which carries a well known form 50 of push button 63. When partially depressed, the contact 63' on the member 62 engages the contact 64 of the resistance device 65, closing the circuit through these contacts and the resistance device 65. More 55 pressure brings the contacts 66 and 67 together, closing the circuit and eliminating the resistance device 65.

I have illustrated these several embodiments of my invention not with any intention of being limited to the forms and details thereof, but merely for the purpose of illustrating the invention. I contemplate numerous and extensive departures from the forms and details illustrated in the drawings.

I claim:

1. In a device of the class described, the combination of a hollow casing long in proportion to its width and low in proportion to its width, one end of the casing being 70 opened and the other closed by a wall having a hole therein, a contact spring completely concealed and covered by said casing, a strip of insulating material insulating said spring from the bottom of the casing upon which it is mounted with the terminal end adjacent the opening in the closed end of the casing, a second contact spring mounted in said casing above the first contact spring, a layer of insulating material between said 75 contact springs, said second contact spring having one of its ends extending through the open end of the casing and accessible from the outside of said casing, the outside end of such contact spring being depressed 80 to form a catch for the finger of the operator, the top of the casing being depressed for the head of a screw and a screw passing through the top and bottom walls of the casing, the contact springs and intervening 85 layers of insulating material and having its head seated in the depression in the top.

2. In a device of the class described, the combination of a hollow casing long in proportion to its width and low in proportion to its width, a contact spring completely concealed and covered by said casing, a strip of insulating material insulating said spring from the bottom of the casing upon which it is mounted with the terminal end adjacent one end of the casing, a second contact spring mounted in said casing above the first contact spring and a layer of insulating material between said contact springs, said 90 second contact spring having one of its ends extending through the casing and accessible from the outside of said casing, the outside end of said second contact spring having a catch formed thereon for the finger of the operator.

3. In a device of the class described, the combination of a support, a contact spring mounted on the support, a layer of insulating material between the contact spring and the support, one end of said contact spring being free, a contact on the free end of said spring, a second contact spring, a layer of insulating material between said contact springs, means to connect said contact springs and insulating material to the base, 115 said contact springs, said base and said layer of insulating material being parallel and a catch formed on the free end of the second contact spring and integral therewith.

4. A switch comprising a hollow casing 120 long in proportion to its width and low in proportion to its width, a contact spring completely concealed and covered by said casing, a strip of insulating material insulating said spring from the bottom of the cas- 125 130

ing upon which it is mounted with the terminal end adjacent one end of the casing, a second contact spring mounted in said casing above the first contact spring and a layer of insulating material between said contact springs, and operating means to actuate said second contact spring including a part extending through and accessible from the outside of said casing and having a catch

formed on said part for the finger of the 10 operator.

In witness whereof I have affixed my signature in the presence of two witnesses this 26th day of September, 1913.

RAY H. MANSON.
